UNITED STATES PATENT OFFICE.

FRIEDRICH HAENLE, OF PASING, GERMANY.

ART OF MAKING LEAF METAL.

SPECIFICATION forming part of Letters Patent No. 699,920, dated May 18, 1902.

Application filed September 1, 1900. Serial No. 28,828. (No specimens.)

To all whom it may concern:

Be it known that I, FRIEDRICH HAENLE, a subject of the German Emperor, residing at Pasing, near Munich, Germany, have invented 5 certain new and useful Improvements in the Art of Making Leaf Metal—that is, thin leaves of gold or silver or of any other suitable metal—of which the following is a specification.

10 In the art of making leaf metal as heretofore practiced the metal is first reduced to thin sheets by rolling or hammering, or both. Sometimes the sheets of metal are further spread and reduced in thickness by piling 15 them with alternate sheets of parchment or vellum and subjecting the pile or "mold" to a hammering process. In this way the metal may be made quite thin; but parchment and vellum do not possess the properties which 20 are necessary for the reduction of metal to the thinness of the product known as "leaf" metal. Leaf metal proper has always been produced by assembling the thin sheets between gold-beater skins and hammering the 25 pile thus formed to spread the metal. The metal may be beaten several times in this way, the large sheets from the first beating between skins being cut usually into four parts and placed between skins for a second 30 beating, &c.

The term "leaf metal" is used in this specification to designate the very thin or attenuated leaves of metal which are too frail to be beaten in vellum or parchment and which 35 have only hitherto been beaten in gold-beater skins.

The gold-beater skins hitherto employed are expensive and necessarily of very limited size. The expense of the skins is partly due 40 to the method of preparing them and partly due to the fact that when first used their product is a second grade, and they must be used for a considerable period of time before they are adapted to produce a fine grade of 45 leaf metal, particularly of leaf metal made from the baser metals, such as brass. Thus before gold-beater skins are suitable for beating the baser metals they must be used for one or two years for beating gold or about a 50 year for beating silver. During the first few weeks of use they do not even give perfect re-

sults in beating pure gold or silver. In addition to the great cost of gold-beater skins a large item of expense is due to the fact that they are easily injured or destroyed.

55

I have discovered that a certain paper, the so-called "Pergamyn" paper and papers of similar structure, may be used in beating leaf metal in lieu of gold-beater skins. This paper is not only much cheaper than the gold-beater skins, but it is better suited for this purpose, producing leaf metal of better finish and more uniform texture. The Pergamyn paper is especially valuable in the beating of metals by machinery, as it works perfectly 60 under a power-hammer, whereas when gold-beater skins are used the beating-machine must be frequently stopped to permit the package of leaf and skins to cool. The same heating takes place in beating gold with paper; but in the case of paper the heating is 65 advantageous, as it causes the metal to yield or spread more rapidly and the paper is not injured by the heat, whereas the skins when hot deteriorate and also retard the spreading 70 of the metal. The pile of sheets of metal and Pergamyn paper may be beaten by machinery or by hand in the usual manner.

The Pergamyn paper, which I prefer to use, is manufactured substantially as follows: A 75 suitable quantity of cellulose produced by indirect boiling (following the system of Mischlerlich) or in any other suitable and desired manner is mixed with glue and alum in proper proportions and this mixture subjected to the action of suitable beating or disintegrating and mixing apparatus until the fiber is scarcely visible and the mass is of a gelatin-like consistency and has a glassy appearance. The material prepared as above 80 indicated is then rolled into sheets and dried by paper-making machinery in the ordinary manner. This paper is made in different 85 thicknesses and weights.

As above stated, I am aware that various 90 materials—such as parchment, vellum, and some papers—have been used in the early stages of beating metal; but I believe myself to be the first to use paper in lieu of gold-beater skins in the beating of leaf metal. It 95 is to be understood, therefore, that my invention relates to the final steps in the manufac-

ture of leaf metal—that is, to the steps in which the metal is reduced to extreme thinness.

What I claim as my invention, and desire 5 to secure by Letters Patent, is—

The improvement in the art of beating gold and other metals into leaf metal which consists in assembling the sheets of metal, for the final beatings, with alternate sheets of

“Pergamyn,” or substantially similar paper, 10 and then beating the sheets so assembled in the usual manner.

In witness whereof I have hereunto set my hand in presence of two witnesses.

FRIEDRICH HAENLE.

Witnesses:

HCH. KACHEL,

GEORGE P. BURNS.
